UNITED STATES PATENT OFFICE.

STEPHEN O. DOUGHERTY, OF TORONTO, ONTARIO, CANADA.

SHADE AND CURTAIN HANGER.

1,392,405.

Specification of Letters Patent.

Patented Oct. 4, 1921.

Application filed May 7, 1919. Serial No. 295,268.

To all whom it may concern:

Be it known that I, STEPHEN O. DOUGHERTY, citizen of the United States, residing at Toronto, in the county of Jefferson and State of Ohio, have invented certain new and useful Improvements in Shade and Curtain Hangers, of which the following is a specification.

This invention relates to an improved shade and curtain hanger and has as its primary object to provide a device of this character which may be easily and inexpensively constructed and which may be applied without difficulty.

15 The invention has as a further object to provide an improved type of hanger bracket which may be struck from suitable sheet metal.

20 And a still further object of the invention is to provide a shade and curtain hanger which will be neat in appearance and wherein the shade holders employed may be adjusted to accommodate shade rollers of different lengths.

25 Other and incidental objects will appear hereinafter.

In the drawings:

Figure 1 is a perspective view showing my improved hanger in connection with a window casing,

Fig. 2 is a longitudinal sectional view taken through one of the brackets employed,

Fig. 3 is a transverse sectional view taken through one of the brackets,

35 Fig. 4 is an end elevation of one of the shade roller holders,

Fig. 5 is a perspective view of a modified form of bracket,

Fig. 6 is a perspective view of a further modified form of bracket,

Fig. 7 is a similar view of another modified form of bracket,

Fig. 8 is a perspective view of still another modified form of bracket,

45 Fig. 9 is a similar view of a further modified form of bracket, and

Fig. 10 is a perspective view on a reduced scale showing a still further modified form of bracket.

50 In carrying the invention into effect, I employ companion brackets 10 which are each formed from a piece of suitable resilient sheet metal and comprise a substantially triangular shaped bracket body. In mounting the brackets in position, the inner vertical margin of each of the brackets is, as

particularly shown in Fig. 1, seated against the outer vertical edge of a window casing and is secured thereto by spaced screws or other suitable fastening devices. Struck 60 from these margins of the bracket bodies are laterally and inwardly directed lugs 12 which seat against the front face of the window casing and are also secured thereto by suitable fastening devices. Extending 65 laterally and inwardly from the lower ends of the bracket bodies are channel guides 13 seating flat against the front face of the window casing. Slidable within these guides are shade roller holders 14. These holders 70 are each formed with spaced openings and formed for selective engagement in said openings are thumb screws 15 adjustable to coact with the guides 13 for securing the holders in adjusted position longitudinally 75 of the guides. Thus, the holders may be positioned either toward or away from each other for receiving shade rollers of different 80 lengths. The laterally and outwardly directed arm of one holder is, as shown in detail in Fig. 4, provided with a slot 16 opening through the front edge of said arm while the arm of the other holder is provided with spaced openings 16'. These slots and openings are, as will be readily understood, 85 adapted to receive the trunnions of a shade roller and, in this connection, it will be observed that by forming the slot 16 to extend in opposite directions from the mouth thereof as well as providing a pair of the openings 16', the holders may be reversed end for end upon the guides so that the arms of the 90 holders may be disposed at the inner edges of the side portions of the window casing. Furthermore, the holders may be presented 95 inwardly toward the window upon the guides. When so disposed the arms of the holders will then project inwardly toward the window for supporting a shade close to the window pane. Formed from the upper 100 margins of the bracket bodies are laterally and outwardly directed flanges 17 provided at their outer ends with depending lugs 18. At their outer end portions, these flanges are provided with slots 19 extending into the 105 lugs. Similar slots 20 extend throughout the major portion of the length of the flanges. The slots of each bracket are divided by an intermediate transverse web 21. Slidably through the slots 19 are curtain 110 pole arms 22 slidably connected with the flanges 17 by eyelets 23 projecting freely

through the slots 20 and secured to the inner ends of said arms. At their outer ends the arms are provided with depending loops 24 adapted to support a curtain pole and 5 threaded through the outer terminals of the loops are set screws 25 adjustable to impinge against the pole for firmly securing the pole upon the arms. Thus, a curtain and shade may be suspended from the hanger in 10 front of the window and in this connection it will be observed that the arms 22 may be adjusted upon the brackets for positioning the curtain either toward or away from the window.

15 In Fig. 5 of the drawings I have shown a slightly modified form of bracket. In this modification, a sheet metal bracket body 26 is employed. This bracket body is, as suggested, adapted to be secured at its inner 20 margin to the inner edge of a window casing and is provided with a laterally and outwardly directed lug 27 to overlie the front face of the casing to which the lug is secured. Formed on the bracket body at its 25 lower end is a laterally and outwardly directed channel guide 28 adapted to overlie the front face of the casing and provided with a longitudinal slot 29. This guide is adapted to receive a shade roller holder in 30 the manner shown in connection with the preferred construction. Formed from the upper margin of the bracket body is a laterally and inwardly directed flange 30 continued at its outer end to provide a curtain pole loop 31. Adjustable through the outer end of said loop is a binding screw 32 for the curtain pole. As will be seen 35 this modified structure provides a very simple type of bracket.

40 In Fig. 6 I have illustrated a further modified form of hanger bracket. In this modification, a bracket body 33 is employed, this bracket body being constructed from a piece of suitable resilient sheet metal, as in 45 the other forms of the invention, and being adapted to be secured at its inner margin to the outer edge of one side strip of a window casing. Formed from the bracket body is a laterally and inwardly directed lug 34 corresponding to the lug 27 of the prior modification. At its upper margin, the bracket body is provided with a longitudinal slot 35 and extending inwardly from the bracket 50 at its upper outer corner is a lateral lug 36 provided with a slot 37 lying in a plane with the slot 35. These slots are adapted to receive a curtain pole arm as in the preferred construction. Formed in the lower end portion of the bracket body adjacent its 55 outer edge is a vertical slot 38 and slidably through this slot is a shade roller holder 39 which, as shown, is similar to the holder 15 of the preferred construction.

In Fig. 7 I have shown a still further 60 modified form of the invention. In this

modification a sheet metal bracket body 40 is employed. This bracket body is designed to be secured at its inner margin to the outer vertical edge of one side strip of a window casing and is provided adjacent its 70 upper end with a laterally and inwardly directed lug 41 adapted to be secured to the front face of the casing. Formed on the outer end of the bracket is a curtain pole loop 42 through the outer end of which is 75 adjustably fitted a binding screw 43 for the pole. Extending from the outer edge of the lower end portion of the bracket body is an outwardly directed flange 44 in which is formed a slot 45. Struck from the lower 80 end portion of the bracket in the rear of this flange is a pair of oppositely disposed lugs 46. A channel guide 47 is employed in connection with the bracket body, this 85 guide being provided with a longitudinal slot 48 and being adapted to receive a shade roller holder as suggested in connection with the other forms of the invention. At its inner end the guide is provided with a laterally directed lug 49. This lug is insertable 90 through the slot 45 of the flange 44 to engage beneath the lugs 46 for connecting the guide with the bracket body. As will be seen, this modification provides a very simple type of bracket and a construction 95 wherein the shade roller guide is detachable.

In Fig. 8 of the drawings I have shown a still further modification. A sheet metal bracket body 50 is employed. Formed from the inner margin of this bracket body is a laterally and outwardly directed flange 51 at the upper end of which is provided an inwardly directed lug 52 above which is arranged an outwardly directed lug 53. The flange and these lugs are designed to be secured to the front face of a window casing for connecting the bracket thereto. Projecting laterally and inwardly from the lower end of the flange 51 is a slotted guide 54 for receiving the shade roller holder. Formed from the upper margin of the bracket body is a laterally and outwardly directed flange 55 continued at its outer end to provide a curtain pole loop 56. The outer end of this loop is formed to adjustably receive a binding screw therethrough. Formed in the outer end portion of the bracket body is an opening 57. This opening is designed to receive a curtain rod. Thus, an ordinary curtain may be suspended from the pole within the loop 56 while a shorter or valance curtain may be suspended from the rod within the opening 57. This 110 modification, therefore, provides a particularly desirable construction.

In Fig. 9 I have shown a further modified form of the invention. In this modification a bracket body 58 is employed. Formed from the inner margin of the 130

bracket body is a laterally and outwardly directed flange 59 corresponding to the flange 51 of the prior modification and extending inwardly from the bracket body at 5 the upper end of the flange 59 is a lug 60 corresponding to the lug 52 of the prior modification. Projecting inwardly from the lower end of the flange 59 is a channel 61 designed to receive a shade roller. 10 Formed in the upper edge of the bracket body adjacent its outer end are spaced notches 62 each of which is adapted to receive a curtain pole and formed in the upper margin of the bracket body adjacent its 15 inner end is an opening 63 designed to receive a curtain rod. Thus, three curtains in all may be suspended from this bracket. In Fig. 10 I have shown a still further modification wherein a bracket body 64 is 20 employed. Formed from the inner margin of this bracket body is a vertical flange 65 and formed from the upper margin of the bracket body is a horizontal flange 66. At its lower end, the flange 65 is bent to provide a suspension loop 67 above which the bracket body is formed with a laterally and 25 outwardly directed arm 68 designed to re-

ceive a shade roller. Formed from the outer end of the flange 66 is a curtain pole loop 69. Thus, a curtain may be suspended from a 30 pole or rod within this loop as well as a pole or rod within the loop 67.

Having thus described the invention, what is claimed as new is:

1. A device of the character described including a bracket body formed at its inner margin for receiving fastening devices therethrough and having its inner margin slit from the inner edge of the body to define a laterally directed stop flange lying in 35 40 advance of the rear edge of the bracket body.

2. A device of the character described including a bracket body having its inner margin slit from the inner edge of the body 45 to define a laterally directed flange and provided at its lower end with a laterally directed guide integral with the body and formed with confronting flanges for slidably connecting a shade roller holder with 50 the guide.

In testimony whereof I affix my signature.

STEPHEN O. DOUGHERTY. [L. S.]

It is hereby certified that in Letters Patent No. 1,392,405, granted October 4, 1921, upon the application of Stephen O. Dougherty, for an improvement in "Shade and Curtain Hangers," an error appears requiring correction as follows: In the grant and in the heading to the printed specification the residence of the patentee is erroneously given as "Toronto, Ontario, Canada," whereas said residence should have been given as *Toronto, Ohio*; and that the said Letters Patent should be read with this correction therein that the same may conform to the record of the case in the Patent Office.

Signed and sealed this 15th day of November, A. D., 1921.

[SEAL.]

KARL FENNING,
Acting Commissioner of Patents.
